UNITED STATES PATENT OFFICE.

FERDINAND MEYROSE, OF ST. LOUIS, MISSOURI.

TUBULAR LANTERN.

SPECIFICATION forming part of Letters Patent No. 269,808, dated December 26, 1882.

Application filed September 29, 1882. (No model.)

To all whom it may concern:

Be it known that I, FERDINAND MEYROSE, of St. Louis, in the State of Missouri, have invented Improvements in Tubular Lanterns, of which the following is a specification.

This device relates to that class of lamps for outside illuminating purposes that are provided with air-tubes for feeding the flame, and particularly the construction of the air-chamber which surrounds the dome of the lantern, and from which the air-tubes are fed with air at their upper ends, and also to the construction of the dome. Previous devices have the air-inlets to the annular chambers too much exposed, thereby rendering the light uncertain for outside illuminating purposes when there are extraordinary drafts of wind. I have found from experience that devices provided with perforations for admission of air are not reliable, and although I am aware that such have been made, yet they do not accomplish the purpose of a steady light in a high wind in an exposed position.

The object of my invention is to overcome these difficulties by a more practical construction.

In my present improvement I dispense with perforations or air-inlets in the floor or top of the chamber, and instead thereof I leave a space beneath the inner wall and extend the floor inwardly, so as to be near to the vertical side of the dome, the floor being formed with radial ribs to prevent the inner wall coming in contact with the floor, and thus providing the desired space in an isolated position where the air can reach the entrance to the chamber, while said entrance is well shielded from strong currents of air on the outside of the lamp or lantern, especially when the device is, as signaling-lanterns, revolved or swung round. Under and close to the flange of the cap-plate of the dome I locate another flange or collar, which together form a narrow annular opening. The effect of this added flange is such as to prevent the most violent wind from influencing the flame objectionably, as this flange prevents any upward current of air produced by deflection from the top of the main chamber from entering violently beneath the cap.

In order that the invention may be fully un-

derstood, I will proceed to describe it with reference to the accompanying drawings, in which—

Figure 1 is a perspective view of my improved annular air-chamber, the dome having been removed. Fig. 2 is a bottom view thereof, the dome being in position. Fig. 3 is a vertical section on the line 3 3, Fig. 2.

A represents the annular air-chamber; B, the air-tubes leading to the burner; C, the hooks by which the handle is attached, and D, the dome of a tubular lantern.

The air-chamber is formed with a floor plate, a, having inverted radial grooves a', forming ribs a², a top plate, b, inclined outwardly and formed on its inner edge with downturned flanges b' and recesses or openings b², the lower edges, b³, of the flanges being inclined, and a vertical ring, c, located midway between the outer and inner edges of the top plate, forming the inner wall of the inner air-chamber, e', and having its lower edge, c', resting on the ribs a², so as to provide entrances c² above the floor and beneath the ring.

The dome D is formed of a cylinder, d, fitting closely the sides of the flanges b' and binding tightly on the upper end of the chimney or globe, as usual, and having vertical lips or tongues d', engaging through slits d² in the cap-plate E, so as to leave annular openings d³.

Located beneath the opening d³ is a down-turned collar, d⁴, conforming to the shape of the outer portion of the cap-plate E.

There are studs on the sides of the cylinder, which, being inserted through the recesses or openings b² in the top plate of the air-chamber, engage by turning the dome with the inclined edges b³ of the flanges b' to hold the dome in place.

A space, e, is left between the dome-cylinder and inner edge of the floor for the passage of outer air to the air-chamber e'.

In a stationary lamp with an air-chamber made as described the wind may come from any direction, and it will always feed the flame with sufficient fresh air. In using any air-chamber made of two or more sheets of metal that are placed close around the globe or dome of lantern, even if there be plenty of holes punched in the top or bottom, if a strong wind is blowing it will certainly smother the flame, as, in-

stead of admitting air into the chamber, it will take the air out of the lamp and extinguish the flame.

The two flanges—one on the cap-plate and one just below the cap plate on the cylinder—close to the neck of the dome are a great advantage. The top flange is common to all lanterns; but the lower flange serves to prevent a rising current of air striking under the upper flange, and thereby disturbing the draft of the lamp and making the flame smoke and go out.

Having thus described my invention, the following is what I claim as new therein and desire to secure by Letters Patent—

1. The combination of an annular air-chamber having inclined top plate, *b*, floor-plate *a*, and vertical ring *c*, and the dome *D*; fitting the

top plate closely and leaving a space, *e*, between the floor-plate and its cylinder, as set forth. 20

2. An annular air chamber, *A*, formed with floor-plate *a*, having radial grooves *a'*, forming ribs *a''*, a top plate, *b*, and vertical ring *c*, located about midway between the outer and inner edges of the top plate, forming inner and outer annular air-chambers, *c'' e'*, and resting on the ribs of the floor-plate, as set forth. 25

3. The dome *D*, in combination with the described air-chamber, the dome fitting the top plate closely and leaving a space, *e*, between the cylinder and floor-plate, as set forth. 30

FERDINAND MEYROSE.
